CATHODE STRUCTURE

Paul Georges Chevigny, New York, N. Y., assignor
to Federal Telephone and Radio Corporation,
Newark, N. J., a corporation of Delaware

Application February 6, 1943, Serial No. 474,968

6 Claims. (Cl. 250—27.5)

1

This invention relates to improvements in cathode structures and methods of assembling the same, and more particularly to indirectly heated cathodes for vacuum tubes.

An object of this invention is to provide an improved, easily assembled cathode structure.

Another object of this invention is to provide an improved novel cathode assembly.

A further object of this invention is the provision of an improved indirectly heated cathode comprising an easily assembled, closely spaced spiral or a plurality of interwound spirals, presenting a continuous emitting surface having a relatively large emitting area.

Other objects and advantages of the present invention will become apparent from the following detailed description of a preferred embodiment of the invention, together with a modification thereof, illustrated in the accompanying drawing in which:

Fig. 1 is a longitudinal sectional view of a cathode assembly formed in accordance with the present invention;

Fig. 2 is a bottom view of the assembly illustrated in Fig. 1; and

Fig. 3 is a plan view of a composite interwound cathode, which may be used in connection with the assembly illustrated in Fig. 1.

In the preferred form of invention shown in Figs. 1 and 2, the cathode 10 consists of a single spiral of pre-set carburized tungsten wire, the turns of which are closely spaced so that they will form a substantially continuous outer emitting surface. The cathode 10 is slipped over a plurality of supporting rods 16 formed, for example, of tungsten. These rods are circumferentially spaced in such a manner that their common outer circumference is substantially equal to the inner periphery of the spiral cathode; as a result the cathode will fit snugly about the rods and the rods will prevent relative lateral movement of the cathode spiral.

The cathode 10 is held on the rod 16 against longitudinal movement between a pair of end rings 18 and 20 which may be, for example, tantalum wires welded to and about the rods 16.

The rods 16, illustrated as four in number are preferably mounted in a supporting member 22, as more clearly shown in Fig. 2, this supporting member being held in place, in turn, by a rod 24 serving as a cathode lead and projecting through the seal of the vacuum tube (not shown).

The member 22 may be formed with a radial slot 26 through which pass a pair of heater filament leads 28 and 30. The centrally positioned

2

lead 28 extends downwardly substantially to the bottom of the cathode 10, and at this point is connected to one end of a concentric spiral filament 32. The upper end 34 of the filament 32 is connected to the second lead 30. The leads 28 and 30 are also adapted to pass through and be supported by the vacuum tube seal.

In place of a single closely wound spiral cathode 10, there may be provided a cathode in the form of two or more widely spaced spirals screwed one into the other, the spacing between spirals being such that they will form a continuous emitting surface when fully interwound. An arrangement illustrating two such spirals forming a composite cathode is illustrated in Fig. 3. This figure shows the spiral 50 partially screwed into the spiral 52. In use, the two spirals would be screwed together so that total length of the cathode would be the same as that of a single spiral cathode such as illustrated in Fig. 1; they have been illustrated as partially unscrewed in Fig. 3 solely for the sake of clarity.

The advantages of the foregoing invention will, it is believed, be clear to those skilled in this art. A cathode of the form disclosed in which the turns are so closely spaced as to be touching one another will form a continuous emitting surface which will have a greater emitting area than a comparable cathode wound, for example, from flat bands. This is due to the fact that the emitting surface is increased by half of the circumference of each turn relatively to its diameter or in the ratio of

35

 $\frac{\pi}{2}:1$

This will result in appreciable gain although not entirely proportional to the increased area, since the electrons emitted between the wires are more difficult to draw out. The fact that in all cases the turns of the spiral are touching to form a substantially closed cylinder permits the advantageous use of this type of cathode with a filament which is adapted to heat the cathode by bombardment. One of the outstanding advantages of the present structure lies in its ease of assembly. It is only necessary to attach one end ring such as the ring 18 about the supporting rods 16, slide the cathode over the rods against this ring, and then add the ring 20 at the other end of the cathode, squeezing the cathode against the ring 18, and attaching the ring 20 to the supporting rods.

Other advantages of the present structure together with obvious modifications thereof, all

coming within the scope of the present invention as set forth in the objects and claims, will be apparent to those skilled in this art.

I claim:

1. A cathode for electron discharge devices comprising, in combination, a supporting member, a plurality of circumferentially positioned rods mounted in said supporting member, a ring extending about and attached to all of said rods, a closely spaced helical winding of substantially uniform diameter extending about said rods and supported by said ring and unattached to the rods, and a second ring extending about and attached to all of said rods at the other end of said winding for holding the same in place on 10 said rods between the two rings.

2. The combination according to claim 1, in which said winding consists of a single closely spaced spiral of wire forming a continuous outer surface.

3. The combination according to claim 1, in which the common outer circumference of the circumferentially positioned rods is substantially equal to the inner periphery of the rings and of the winding, whereby the rods hold the winding 25 against lateral movements and the rings hold the winding against longitudinal movement.

4. A cathode for electron discharge devices comprising, in combination, a supporting member, a plurality of circumferentially positioned rods mounted in said supporting member, a ring extending about and attached to all of said rods, a closely spaced helical winding of substantially 20

uniform diameter extending about said rods and supported by said ring, said winding consisting of a plurality of interwound closely spaced spirals forming a continuous outer surface, and a second ring extending about and attached to all of said rods at the other end of said winding for holding the same in place on said rods between the two rings.

5. An electrode for electron discharge devices comprising, in combination, a supporting member, a plurality of circumferentially positioned rods mounted in said supporting member, a cylindrical member of substantially uniform diameter extending about said rods and capable of longitudinal movement in relation to said rods, and means for preventing longitudinal movement of said cylindrical member, said means comprising solely a pair of rings attached to each of said rods adjacent and abutting opposite ends of said cylindrical member.

6. An electrode for electron discharge devices comprising, in combination, a supporting member, a plurality of circumferentially positioned rods mounted in said supporting member, a closely spaced helical winding of substantially uniform diameter extending about said rods and capable of longitudinal movement in relation to said rods, and means for preventing longitudinal movement of said winding, said means comprising solely a pair of rings attached to each of said rods adjacent and abutting opposite ends of said winding.

PAUL GEORGES CHEVIGNY.
